UNITED STATES PATENT OFFICE.

PETER SPOHN VAN WAGNER, OF STONEY CREEK, TOWNSHIP OF SALT-FLEET, CANADA, ASSIGNOR TO HIMSELF AND ALBERT E. CARPENTER, OF SAME PLACE.

IMPROVEMENT IN ADJUSTABLE TRACE-FASTENING.

Specification forming part of Letters Patent No. **96,852**, dated November 16, 1869.

To all whom it may concern:

Be it known that I, PETER SPOHN VAN WAGNER, of Stoney Creek, township of Saltfleet, county of Wentworth, Province of Ontario, Dominion of Canada, have invented a new and improved Adjustable Trace-Fastening; and I do hereby declare that the following is a full, clear, and exact description thereof, which will enable others skilled in the art to make and use the same, reference being had to the accompanying drawings, forming part of this specification.

The present invention relates to an improvement in adjustable trace-fasteners, and consists in the employment of a volute spring, in combination with a T or ornamental arrow-head, and the whiffletree tip or socket, whereby a stiff spring occupying but little space is produced, to permit the tip to be more firmly secured upon the whiffletree.

I am aware that spiral springs have been used in this connection, but in order to produce the requisite strength, it is necessary that such springs be made very long, and they therefore occupy so much of the hollow tip as to prevent the latter from being firmly secured upon the whiffletree.

Figure 1 represents a section of my device. Figure 2 is a plan of the same.

Similar letters of reference indicate corresponding parts.

In this case, A represents a metal socket for the end of the whiffletree, on one end of which socket the hook proper, B, is cast, the said

hook flaring, as shown in the accompanying drawing, and has a groove, C, on its top, and also a groove, D, on the top sides of the hook proper, in which the T or ornamental arrow-head E will rest when locked, the spring F serving to hold the said T or arrow-head firm in its place.

In fig. 1, the trace G is shown as having been just slipped over the whiffletree-fastening, and in order to lock the same, the T or ornamental arrow-head E is turned crosswise to the button-hole in the trace, as shown in fig. 2.

The spring F is secured in its place by the washer H, which is prevented from slipping off the stem of the arrow-head either by means of flattening out the end of the said stem, or by means of a pin passing through the said stem, as may be deemed best in practice.

Having thus described my invention,

What I claim as new, and desire to secure by Letters Patent, is—

The trace-fastener herein described, consisting of the grooved socket A, arrow-head E, and spiral spring F, so constructed that the arrow-head has only sufficient longitudinal movement to allow it to be turned round in the socket, substantially as specified.

The above specification of my invention signed by me, this 13th day of March, 1869.

P. S. VAN WAGNER.
